PROCESS CONTROL SYSTEM

Donald E. Berger, Bartlesville, Okla., assignor to Phillips Petroleum Company, a corporation of Delaware
Filed May 28, 1959, Ser. No. 816,407
4 Claims. (Cl. 260—683.43)

This invention relates to an improved method of and apparatus for controlling the separation of fluid mixtures by fractional distillation. In accordance with one aspect, this invention relates to an improved method for separating a feed mixture of organic compounds in a fractionation zone into overhead, bottoms, and intermediate product streams, which comprises regulating the temperature of the feed mixture passed to said zone responsive to the concentration of at least one of overhead and bottoms components in said intermediate stream. In accordance with another aspect, this invention relates to an improved method for fractionating a feed mixture of hydrocarbons into overhead, bottoms, and intermediate product streams, which comprises controlling the temperature of the feed passed to said zone responsive to the total concentration of overhead and bottoms materials in said intermediate stream. In accordance with another aspect, this invention relates to an improved method for separating the effluent from a reaction process in a fractionation zone into overhead, bottoms, and intermediate product streams, and wherein said intermediate product is directly recycled to said process, said improvement comprising controlling the temperature of the feed mixture passed to said zone responsive to the concentration of at least one of overhead and bottoms components in said intermediate recycle stream. In accordance with still another aspect, this invention relates to an improved alkylation process wherein said alkylation process hydrocarbon effluent is separated in a confined unitary fractionation zone into a propane containing overhead fraction, a normal butane and alkylate containing bottoms fraction, and an intermediate isobutane containing fraction, said isobutane fraction being directly recycled to said alkylation process, said improvement comprising regulating the temperature of said effluent passed to said fractionation zone responsive to the total concentration of overhead and bottoms components in said isobutane stream.

It is common practice in the petroleum and chemical industries to separate fluid mixtures by means of fractionation columns. These columns are provided with a plurality of liquid-vapor contacting surfaces, such as bubble trays or packing material. Heat is supplied to the lower region of the column to generate a vapor flow and to vaporize the feed mixture which is introduced into the column. A kettle product stream which is rich in the higher boiling constituents of the feed mixture is removed from the lower region of the column. A vapor stream which is rich in the lighter constituents is removed from the upper region of the column. This vapor stream is partially or completely condensed and a portion of the condensed material normally is returned to the column as reflux. Also, in many operations, an intermediate fraction or stream is removed at an intermediate portion of said column. Various systems have been devised to control the operation of such fractionation columns in order to maintain desired degrees of separation of fluid mixtures. These control systems have generally been based upon measurements of flow rates, temperatures and pressures. In recent years, a number of automatic control systems have been devised which are based upon the continuous removal of a sample stream from the column or one of the product streams and a subsequent analysis of the stream to determine the concentration of a partic-

2

ular constituent or constituents. The present invention relates to an improved control system of this general type.

The demand for large volumes of high quality gasolines has brought about the development and commercialization of a number of processes for the conversion of non-gasoline range hydrocarbons into high octane blending stocks. One of these processes, the alkylation of light olefins, such as propylene and butylenes, with isobutane using liquid hydrofluoric acid as the catalyst, has proved to be particularly effective in producing alkylates for aviation and motor fuel blending. As a result of considerable operational experience, this process has now been developed to such an extent that a commercial plant can be controlled by two men per shift to obtain desired product quality with safety. However, a substantial expenditure of laboratory and process engineering time still is required to coordinate the operations and to manipulate the process variables toward the economic optimum. In accordance with the present invention, an improved control system for such an alkylation process and for a fractionation column is provided. This control is based upon analyses of sample streams removed from the upper, lower and intermediate regions of the column. The heat and material balances of the column are adjusted in response to these analyses so as to provide at least three output product streams of desired composition.

Accordingly, it is an object of this invention to provide an improved method for analyzing and for controlling the separation of fluid mixtures. Another object of this invention is to provide a method of and apparatus for controlling the operations of fractionation columns in response to an analysis of a sample stream removed from the column. A further object of this invention is to provide an improved control system for an alkylation process. A still further object of this invention is to provide a control system for a fractionation column which operates to provide three product streams of desired composition.

Other aspects, objects, as well as the several advantages, of this invention are apparent from a study of the disclosure, the drawing and the appended claims.

In accordance with a basic concept of the present invention, I provide an improved method for separating a feed mixture of organic compounds which comprises passing said feed mixture to be separated to a fractionation zone, recovering overhead, bottoms, and intermediate product streams from said fractionation zone, said improvement comprising regulating the temperature of said feed mixture passed to said zone responsive to the concentration of at least one of overhead and kettle product components in said intermediate stream, said regulated temperature being an optimum feed temperature at which the concentration of impurities in said stream is at a minimum. I use the term "temperature" as a measure of the enthalpy or heat content of the feed stream. It is actually the enthalpy of the feed stream that is regulated in accordance with this invention. Because temperature is easier to measure than enthalpy and is proportional to enthalpy, the temperature of the feed stream is measured and controlled. As I refer to the temperature of the feed stream hereafter, I mean the enthalpy of the feed stream as determined by the temperature of said stream.

More specifically, in accordance with the present invention, an improved method is provided for separating a feed mixture of hydrocarbons comprising normal butane, isobutane, alkylate, propane, and lighter materials into a first stream comprising propane and lighter

materials, a second stream comprising normal butane and alkylate and a third stream comprising isobutane, said improvement comprising directing a stream of such a feed mixture to be separated to a fractionation zone, removing such a first stream, second stream and third stream from said zone, withdrawing a sample stream from said third stream, measuring the total concentration of propane and normal butane in said sample stream and adjusting the temperature of said fractionation zone feed mixture in response to the measurement so as to maintain an optimum feed temperature at which the total concentration of propane and normal butane in said isobutane stream is at a minimum.

In accordance with a more specific concept of the present invention, I provide an improved method of measuring and controlling the operation of a chemical process, for example, the alkylation of olefins and isoparaffins in the presence of a catalyst which comprises passing the effluent from such a process to a single confined unitary fractionation zone, removing from said fractionation zone overhead, kettle and intermediate product streams, directly recycling said intermediate product stream to said reaction process, analyzing said intermediate product stream to determine the concentration of overhead and kettle product components present in said intermediate stream, and regulating the temperature of the feed passed to said fractionation zone responsive to the concentration of overhead and kettle product components in said recycle stream, said temperature being an optimum feed temperature at which the concentration of impurities in the intermediate product stream is at a minimum.

In accordance with another concept of the present invention, I provide an improved arrangement of apparatus of an alkylation unit comprising a reactor, means to supply olefins and isoparaffins to said reactor, a fractionation column adapted to separate said alkylation unit effluent into three product streams, means to pass the reaction product from said reactor to said fractionation column, a condenser, a reflux accumulator, means to remove fluid from the top of said column and pass same through said condenser to said accumulator, means to return a portion of the liquid in said accumulator to said column as reflux, means to remove a kettle product from the bottom of said column, means to withdraw an intermediate product from an intermediate portion of said column to be recycled to said alkylation unit reactor, means to measure the overhead product and kettle product components concentration in said intermediate product stream, and means responsive to said measuring means adapted to control the temperature of the feed passed to said column responsive to the concentration of impurities in said intermediate stream.

In accordance with the present invention, the relative loading of the top and bottom sections of a combined depropanizer-deisobutanizer column in a "streamlined" alkylation plant is controlled by manipulating the feed temperature to the column so as to insure a maximum purity of isobutane recycle to the alkylation plant which is withdrawn from said column as an intermediate fraction while producing LPG-quality propane overhead and a normal butane-alkylate kettle product containing a minor amount of isobutane. The manipulation of the column feed temperature is regulated by an optimizing controller responsive to isobutane recycle purity. The optimizing controller seeks and holds an optimum feed temperature at which the concentration of impurities in the isobutane recycle stream is a minimum. Further, the purities of overhead and bottom products withdrawn from the combination column are also controlled by analyzing-recording controllers.

The present invention will be practiced primarily in connection with an alkylation of isobutane with low-boiling olefins, such as butylenes and/or propylene or amylenes. The olefin feed may comprise a butane-butenylene fraction or a butylene-ethylene or butylene-propylene

fraction from a refinery. The conditions of temperature, pressure and time, as well as the ratios of isobutane to olefin and of hydrocarbon to acid, are well known in the art. However, the conditions in the alkylator can be as follows: temperature 50 to 150° F., pressure sufficient to maintain liquid phase, average reaction time of the order of about 1 second to 15 minutes and rapid agitation to maintain intimate contact between acid and hydrocarbon phases. The ratio of isobutane to alkylating agent or olefin will be about 6:1 to 20:1 by weight, acid to hydrocarbon ratio will be about 2:1 by weight. Any suitable liquid alkylation catalyst which is capable of effecting alkylation of the isobutane with the olefin under conditions herein described may be employed. Generally speaking, I employ a liquid inorganic acid, such as anhydrous hydrofluoric acid or concentrated sulfuric acid.

In order to further describe the apparatus and method of this invention, reference is made to the attached drawing. The drawing diagrammatically represents an arrangement of apparatus suitable for the practice of this invention. In order that this invention may be more clearly understood, a brief description of an alkylation process will be made. It is to be understood that the flow diagram is diagrammatical and may be altered in many respects by those skilled in the art and, yet, remain within the scope of my invention.

Referring to the drawing, in detail, there is shown an alkylation reactor or contactor 10 which has an inlet conduit 11 communicating therewith to supply liquid hydrofluoric acid from acid purification unit 12. A hydrocarbon feed stream is introduced into reactor 10 through a conduit 13. A fresh isobutane feed stream is supplied to inlet conduit 13 through a conduit 14. The flow through conduit 14 is regulated by a rate of flow controller 15 which adjusts a control valve 16. An olefin feed stream, which can be a mixture of propylene and butylenes, for example, is supplied to conduit 13 through a conduit 17. The flow through conduit 17 is regulated by a rate of flow controller 18 which adjusts a control valve 19. A recycle isobutane stream, to be more fully described hereinbelow, is introduced into inlet conduit 13 by way of conduit 20. Recycle isobutane stream 20 is regulated by a rate of flow controller 21 which adjusts a control valve 22.

The alkylation reaction is completed in reactor 10 by intimately contacting the hydrocarbons with the hydrofluoric acid catalyst. The hydrofluoric acid-hydrocarbon mixture is removed from reactor 10 through a conduit 23 which communicates with a settler 24. The acid phase in settler 24 is withdrawn through a conduit 25 which communicates with an acid purification unit 12. All or a part of this acid is purified in purification unit 12 by distilling the acid from water and acid soluble oils. The ratio of acid to hydrocarbon supplied to reactor 10 is generally controlled at a selected level between approximately 0.2:1 to 3:1 parts by weight.

The hydrocarbon phase, which may contain some soluble hydrofluoric acid, is removed from settler 24 by means of conduit 25 which communicates with the inlet of a fractionation column 32 that is operated as a combined depropanizer-deisobutanizer column in a "streamlined" alkylation plant. The flow through conduit 25 is regulated by liquid level controller 26 on settler 24 which adjusts valve 27. The hydrocarbon phase passed through conduit 25 to column 32 is passed through heat exchanger 28. A heating medium is circulated through heat exchanger 28 by means of a conduit 29. The flow of heating material through conduit 29 is regulated by a temperature recording controller 31 which adjusts a valve 30 in response to a measurement of the temperature of the fluid entering column 32. The set point of temperature recording controller 31 is manipulated by an optimizing controller to be described more fully hereinafter. The control system of the present invention insures that the feed stream supplied to column 32 is maintained at sub-

stantially a constant temperature which is the optimum feed temperature for the column.

Column 32 is operated so as to separate the isobutane and lighter components from normal butane and the alkylate product. The normal butane and alkylate product are withdrawn as kettle product from column 32 through a conduit 33 by pump 68. A portion of the kettle product is withdrawn from the system for use elsewhere, not shown, through conduit 34. The rate of flow through conduit 34 is regulated by a flow recording controller 35 which adjusts flow control valve 36. The set point of flow recording controller 35 is manipulated by liquid level controller 37 on the bottom of column 32. Liquid level controller 37 maintains a constant liquid level in the bottom of column 32.

The remaining portion of the kettle product removed from column 32 by way of conduit 33 is returned to column 32 by conduit 38, furnace 39 and conduit 40. The flow through conduit 38 is regulated by a rate of flow controller 41 which adjusts a control valve 42. Fuel is fed to direct fired reboiler furnace 39 by means of a conduit 43 which is provided with a flow controller 44 that adjusts a valve 45. Flow controller 44 is reset by temperature recording controller 46. Pressure recorder controller 69 maintains an elevated pressure in line 40 by manipulating throttle valve 70. An elevated pressure is desired in line 40 so as to maintain the contents of line 40 largely in the liquid phase. This makes it possible to heat the contents of line 40 to a temperature of about 450° F. in direct fired reboiler furnace 39. Thermal defluorination of the contents of line 40 is thus effected in furnace 39. That is, organic fluoride compounds present in the bottoms product are decomposed to hydrofluoric acid and light hydrocarbons. The hydrofluoric acid is later removed as a separated liquid phase from accumulator 51 through line 72 and recycled to contactor 10. A sample stream is removed from a lower portion of column 32 through a conduit 47 which communicates with an isobutane analyzer 48. Isobutane analyzer-recorder-controller 48 provides an output signal which is employed to manipulate the set point of rate of flow controller 41 which regulates the amount of kettle product recycled through furnace 39 to column 32 and thereby the amount of reboiling heat.

In actual operation, it is desired that the kettle product contain a minimum amount of isobutane. Analyzer-recorder-controller 48 provides an output signal which is representative of the isobutane concentration of the lower region of column 32. If the measured isobutane concentration should increase above a preselected value, for example, analyzer 48 manipulates the set point of rate of flow controller 41 so as to open valve 42 further. This increases the flow of kettle product recycled through reboiler furnace 39 thereby adding more heat to the bottom of column 32. This increased addition of heat produces an increased flow of vapor upward through column 32 which results in an improved separation of isobutane from the bottoms product. The isobutane passes upward in the column and is removed at an intermediate point in the column as described hereinafter.

Propane and lighter hydrocarbon components, the hydrofluoric acid liberated by thermal defluorination in reboiler furnace 39, and the hydrofluoric acid contained in the feed are removed from the top of column 32 through a conduit 49 which communicates with an accumulator 51 through a condenser 50. The flow through conduit 49 is controlled by means of a pressure controller 52 which adjusts a control valve 53. The effluent from condenser 50 separates into a gaseous phase, a liquid hydrocarbon phase, and a liquid hydrofluoric acid phase in accumulator 51. The small volume of gaseous phase, principally light hydrocarbons with some HF, is removed through conduit 71 to an HF recovery means, not shown. The dense, liquid hydrofluoric acid phase settles to the bottom of the accumulator, is withdrawn through con-

duit 72 and recycled to acid purification unit 12. The liquid hydrocarbon phase, principally propane with some dissolved hydrofluoric acid, is withdrawn from accumulator 51 through conduit 54 which extends a few inches above the bottom of the accumulator so as to avoid withdrawing any liquid hydrofluoric acid. A portion of the liquid hydrocarbons is returned to column 32 as reflux through conduit 55. The flow through conduit 55 is regulated by a rate of flow controller 56 which adjusts a valve 57. The remainder of the liquid hydrocarbons is withdrawn as product through conduit 58. The flow through conduit 58 is regulated by a rate of flow controller 59 which adjusts a control valve 60. The set point of flow recording controller 59 is manipulated by liquid level controller 61 on accumulator 51.

As discussed above, the operation of column 32 is controlled in accordance with this invention in order to separate propane and lighter components from isobutane in the upper section of the column and to separate n-butane and heavier components from isobutane in the lower section of the column. A second sample stream is removed from the overhead conduit 49 through a conduit 62 which communicates with the inlet of a second isobutane analyzer recorder controller 63. The concentration of isobutane in the sample stream removed through conduit 62 normally is quite small because column 32 is operated to remove substantially all of the isobutane at an intermediate point in column 32. Analyzer recorder controller 63 provides an output signal which is representative of this concentration. If the isobutane concentration should exceed a predetermined value, for example, the set point of rate of flow controller 56 is manipulated so as to open valve 57 further to increase the reflux rate. This serves to decrease the amount of isobutane in the upper region of column 32. In view of the above discussion, it should be evident that the two analyzer recorder controllers 48 and 63 cooperate with one another in a manner so as to accomplish an efficient separation between the various fractions in column 32. Loss of isobutane in both top and bottom products is held to a minimum by analyzers which control reflux ratio and boil-up rate. As the feed temperature is decreased, the load in the lower portion of the column is increased at the expense of the load in the upper portion of the column. This results from the fact that cool feed condenses some of the rising vapors at the feed tray thereby decreasing the vapor flow in the upper portion of the column and increasing the liquid flow in the lower portion. As the feed temperature is increased, the load in the upper portion increases relative to the load in the lower portion. At low feed temperatures the low upper column loading, insufficient propane will be forced out the top of the column and, hence, will dilute the isobutane recycle stream to an undesirable extent. At high feed temperatures and low lower column loading, insufficient normal butane will be forced out the bottom of the column and will dilute the isobutane recycle stream. Thus, there exists an optimum feed temperature at which the concentration of impurities, that is, propane and normal butane, in the isobutane recycle stream is at a minimum.

In accordance with the present invention, a sample stream is removed from recycle isobutane conduit 20 through conduit 64 and passed to analyzer 65. Recycle isobutane is withdrawn from column 32 at an intermediate point of column 32. The concentration of normal butane and propane removed through conduit 20 normally is less than 10 percent because column 32 is operated to remove substantially all of the normal butane in the kettle product and substantially all of the propane in the overhead product. Analyzer 65 provides output signals which are representative of the concentration of propane and n-butane in recycle isobutane stream in conduit 20. Signals obtained in analyzer 65, representative of the concentration of both propane and normal butane in sample stream 64, are passed to an analog adder 66

wherein the two concentration signals are added to obtain a single signal which represents total concentration of impurities, that is, propane and normal butane, in the recycle isobutane stream. The single measurement signal obtained in analog adder 66 is passed to optimizing controller 67. The optimizing controller is preferably a Quarie Optimal Controller hereinafter described in more detail. The signal from optimizing controller 67 manipulates the set point of temperature recorder controller 31 so as to adjust motor valve 30 to supply the proper amount of heating medium for heater 28 so as to regulate the feed temperature in conduit 25 passed to column 32. As indicated above, there exists an optimum feed temperature at which the concentration of impurities, that is, propane and normal butane, in the isobutane stream is at a minimum. The optimizing controller seeks and holds this optimum feed temperature by continually adjusting the flow of heating medium through heater 28 by comparing the impurity concentration in recycle isobutane stream after the adjustment with the concentration of impurities prior to the adjustment. The optimizing controller then selects the optimum feed temperature at which the concentration of impurities in the isobutane recycle stream is at a minimum.

The control instruments, as described herein, are commercially available items of manufacture, and it is not intended to limit the invention to any specific type of instrument. Although the instruments, as described, generally supply a pneumatic signal, it is within the scope of the invention to utilize a type of controller which furnishes an electrical signal in which case electrically-operated valves should be used. For example, the temperature recorder controllers and flow recorder controllers can be controllers, such as Foxboro Pneumatic Controller Model 58 available from the Foxboro Instrument Company, Foxboro, Mass.; or Swartwout Autronic Electric Recorder Controller available from the Swartwout Company, Cleveland, Ohio.

Analyzing instruments 48, 63 and 65 can be any commercially available analyzing instrument, such as a gas chromatograph, refractometer, infrared analyzer, and the like. As noted before, analyzer recorder controllers 48 and 63 are preferably of the infrared type and are sensitized to isobutane. Analyzer 65 is preferably a chromatograph and analyzes for both propane and normal butane. Thus, in actual operation, if isobutane is carried overhead from column 32, analyzer 63 senses the isobutane and, accordingly, increases the reflux to column 32 by way of reflux line 55. Increasing the reflux to the top of column 32 will decrease the amount of isobutane coming overhead. Similarly, at the bottom of the column, if there is too little heat being supplied to the reboiler, isobutane will be detected in the lower portion of the column. Accordingly, analyzer 48 senses this isobutane concentration and increases the flow rate of kettle product passed through reboiler 39. By maintaining a constant temperature of the fluid passing from reboiler 39, additional heat is introduced into the bottom of column 32 which, in turn, forces isobutane up the column.

The optimizing controller 67 can be any conventional commercially available instrument which produces a signal output corresponding to the difference between the predicted value of a controlled variable in a system, and the actual value at which the system stabilizes after a change in the controlled variable. Such a controller is the Quarie Optimal Controller manufactured by Quarie Controllers, Sharon, Mass. The Westinghouse Opcon, manufactured by Westinghouse Electric Corp., Pittsburgh, Pa., may also be used. As discussed above, analyzer 65 measures the separate concentrations of propane and n-butane in recycle isobutane stream 20 withdrawn from an intermediate point in column 32 and passes signals proportional to concentration, one signal for propane, another

for n-butane, to analog adder 66. The analog adder sums the two signals and sends a resulting, single signal, proportional to the total concentration of propane and n-butane, to the optimizing controller 67. The optimizing controller 5 compares the signal from the analog adder with the previous signal and then adjusts the heat supplied to the feed passed to column 32. These steps are repeated until the signal from analog adder 66 is a minimum at which condition the fractionator feed temperature is optimum. Analog adder 66 may be a Philbrick K2X amplifier, manufactured by George A. Philbrick Researches Inc., 230 Congress St. Boston 10, Mass.

The Quarie Optimal Controller is discussed in an article appearing in Instruments and Automation, November 15 1956, pages 2212-2216. Since the details and the internal operation of the Quarie controller do not form a part of this invention, except as said controller can be used as previously described, a detailed description thereof is omitted from this specification. However, as one skilled 20 in the art will understand reading this disclosure, the Quarie controller is described herein by reference to the said article which, in turn, refers to other articles. As noted above, the Quarie Optimal Controller is a controller which causes a change in the temperature of the feed to a 25 fractionating column and, then, compares this change in the recycle isobutane impurity concentration with the previous concentration and, then, "hunts," if necessary, by adjusting the heat supplied to the feed stream by way of flow controller 30 until the isobutane impurity concentration is a minimum.

The change in any one of the process variables, as described hereinabove, causes concomitant changes in other process variables. The instrumentation of this invention automatically makes the necessary adjustments so 35 that an overhead product and a bottoms kettle product substantially free of isobutene are continuously recovered from the column. Further, an intermediate fraction comprising essentially isobutane is withdrawn from an intermediate portion of the column which is substantially free of overhead and bottoms product and recycled to an alkylation unit. By utilizing three analyzers, as described above, the heat and material balances in the fractionating column are controlled within quite close limits.

The following is a specific example of operation according to the present invention, as described above in connection with the attached drawing.

EXAMPLE

In a specific example employing a control arrangement 50 described in connection with the drawing, alkylation reactor 10 is operated at 78° F. and at a sufficient pressure to maintain a liquid state. The ratio of isobutane to olefin supplied to reactor 10 based on parts by weight is 8.4 to 1.0. Hydrofluoric acid is employed as the catalyst. 55 This acid is supplied to reactor 10 at a ratio of 1 to 1 based on catalyst to hydrocarbon parts by weight. In contactor 10, each barrel of olefin reacts with 1.2 barrels of isoparaffin to produce 1.7 barrels of total alkylate. The alkylate is removed from settler 24 and passed 60 through conduit 25 and heater 28 where it is heated to a temperature of 100 to 350° F. and introduced into column 32. Column 32 is operated at 300 p.s.i.g., 130° F. top temperature, 350° F. bottom temperature and a reflux to feed ratio of 1 to 1. The compositions and flow rates through the several conduits are as follow:

Table

Olefin feed (17)	5,000 barrels/day
Propylene	1,635 barrels/day
Propane	635 barrels/day
Butylenes	1,660 barrels/day
Isobutane	835 barrels/day
n-Butane	235 barrels/day
Total olefin	3,295 barrels/day
Temperature	90° F.

Table—Continued

Fresh isobutane (14) -----	3,249 barrels/day.
Propane -----	67 barrels/day.
Isobutane -----	3,115 barrels/day.
n-Butane -----	67 barrels/day.
Temperature -----	90° F.
Recycle isobutane (20) -----	29,600 barrels/day.
Propane -----	300 barrels/day.
Isobutane -----	29,000 barrels/day.
n-Butane -----	300 barrels/day.
Temperature -----	90° F.
Hydrocarbon from settler (25) -----	37,000 barrels/day.
Isobutane -----	29,000 barrels/day.
Propane -----	1,000 barrels/day.
n-Butane -----	600 barrels/day.
Alkylate -----	5,600 barrels/day.
Dissolved HF -----	800 barrels/day.
Catalyst (11) -----	37,850 barrels/day.
Wt. percent HF -----	90%.
Temperature -----	78° F.
Contactor (10):	
Pressure, p.s.i.a. -----	115.
Temperature, ° F. -----	95.
Isobutane/olefin mol ratio -----	8.4:1.
Catalyst/hydrocarbon vol ratio -----	1:1.
Alkylate (butane free) -----	5,600 barrels/day.

From the foregoing, it should be evident that there is provided in accordance with this invention an improved control system for a "streamlined" alkylation unit wherein the alkylation unit effluent is passed directly to a combined depropanizer-deisobutanizer column. While the invention has been described in conjunction with a particular reaction of isobutane with light olefins, it should be evident that it is not limited to this specific reaction. Also, the fractionation column control system is adaptable to any system wherein it is desired to separate a fluid mixture into three or more product streams of desired composition.

The terms "overhead product streams" and "bottoms product streams" referred to herein in the specification and the claims refer to one or more of such streams removed from the fractionation column above and below the feed point and withdrawal point of the intermediate product stream. In connection with the specific embodiment described in the accompanying drawing, butane may be withdrawn at some point between the feed point and the very base of the column, as well as an alkylate stream withdrawn from the bottom of the column. Similarly, in the upper region of the column, propane could be withdrawn at some point between the isobutane withdrawal point and the very top of the column, and lighter materials withdrawn from the top.

Also, as discussed hereinbefore, the feed temperature to a fractionation column is controlled or regulated responsive to the concentration of impurities in an intermediate stream withdrawn from the fractionation zone. Impurities measured in the intermediate fraction may be either lighter, i.e., lower boiling, overhead materials or higher boiling bottom product materials or the total concentration of both bottom and overhead product materials can be advantageously measured in the intermediate product stream.

Reasonable variation and modification are possible within the scope of the foregoing disclosure, the drawing and the appended claims to the invention, the essence of which is that there have been provided a method and an apparatus for automatically optimizing a fractionator feed temperature, the method according to the invention comprising passing an effluent stream from a reaction system, such as an alkylation unit, to a fractionation zone, fractionating said effluent stream into an overhead, bottoms, and an intermediate product stream, recycling said intermediate stream to said reaction system, analyzing said intermediate fraction for concentration of over-

head and bottoms impurities present in said intermediate stream, regulating the temperature of the feed passed to said fractionation zone responsive to the concentration of contaminants or impurities in said intermediate recycle stream and seeking or holding an optimum feed temperature at which the concentration of impurities in said recycle stream is at a minimum; the apparatus comprising, in combination, a reactor, a fractionation column, means to conduct reactor effluent to said column, overhead vapor withdrawal means, condensing means and accumulator means, bottom withdrawal means, reboiler means and means at an intermediate portion of said column for withdrawing an intermediate fraction, means to analyze said intermediate fraction for overhead and bottoms contaminants in said intermediate fraction, means to compare the analyzed concentration with a previously determined concentration and means to regulate heat supplied to the column feed in order to find and hold an optimum fractionator feed temperature at which the concentration of impurities in said intermediate stream is at a minimum.

I claim:

1. In an alkylation process wherein an isoparaffin is reacted with an olefin under alkylation conditions to produce an alkylation reaction mixture effluent, the improvement which comprises directly passing said effluent as a feed mixture into a unitary confined fractionation zone, withdrawing an overhead product from an upper portion of said fractionation zone, introducing a portion of said withdrawn overhead product into an upper portion of said fractionation zone, withdrawing a kettle product from a lower portion of said fractionation zone, introducing heat into said lower portion of said fractionation zone, withdrawing an intermediate product as an intermediate fraction from an intermediate portion of said fractionation zone, analyzing said overhead product to determine the concentration of said intermediate product in said overhead product, adjusting the rate of flow of reflux into said zone so as to maintain the concentration of said intermediate product in said overhead product at a minimum, analyzing said kettle product to determine the concentration of said intermediate product in said kettle product, adjusting the rate of flow of kettle product from said zone so as to maintain the concentration of said intermediate product therein at a minimum, analyzing said intermediate fraction to determine the concentration of overhead and kettle products in said intermediate fraction, and adjusting the temperature of the fractionation zone feed in response to the analysis of said intermediate fraction so as to tend to maintain the analyzed concentration at a minimum value and hold the fractionation zone feed temperature at an optimum temperature.

2. A process for separating the effluent from an alkylation process consisting essentially of propane, normal butane, isobutane and alkylate which comprises passing said effluent as a feed mixture into a unitary confined fractionation zone, withdrawing an overhead product stream comprising propane from an upper portion of said zone, introducing a portion of said withdrawn overhead product stream into an upper portion of said zone, withdrawing a kettle product stream comprising normal butane and alkylate from a lower portion of said zone, withdrawing an intermediate product stream comprising isobutane from an intermediate portion of said zone, adding heat to the lower portion of said zone, analyzing the overhead product stream to determine the concentration of isobutane, adjusting the reflux passed to said zone responsive to said isobutane concentration, analyzing the kettle product stream to determine the concentration of isobutane, adjusting the flow of kettle product through a heating zone in the lower portion of said zone, analyzing said intermediate product to determine the concentration of propane and normal butane impurities in said intermediate product, comparing said analyzed impurity concentration with an earlier determined impurity concentration, and

11.

adjusting said fractionation zone feed temperature responsive to said comparison so as to maintain an optimum fractionation zone feed temperature at which the concentration of said impurities in said intermediate product is at a minimum.

3. A process for separating a stream comprising first, second and third components which comprises passing said stream as a feed mixture into a unitary fractionation zone, withdrawing an overhead product stream comprising said first component from an upper portion of said zone, introducing a portion of said withdrawn overhead product stream into an upper portion of said zone as reflux, withdrawing a kettle product stream comprising said second component from a lower portion of said zone, withdrawing an intermediate product stream comprising said third component from an intermediate portion of said zone, adding heat to the lower portion of said zone, analyzing the overhead product stream to determine the concentration of said third component therein, adjusting said reflux responsive to said third component concentration in said overhead stream, analyzing the kettle product stream to determine the concentration of said third component therein, adjusting the flow of kettle product through a heating zone, responsive to said third component concentration in said kettle product stream, analyzing said intermediate product to determine the concentration of said first and second components in said intermediate product, comparing said analyzed concentration of said first and second components with an earlier concentration of said first and second components and adjusting said fractionation zone feed temperature responsive to said comparison to maintain an optimum fractionation zone feed temperature at which the concentration of said first and second components in said intermediate product is a minimum.

4. A process for separating a stream comprising first, 35

12.

second and third components which comprises passing said stream as a feed mixture into a unitary fractionation zone, withdrawing an overhead product stream comprising said first component from an upper portion of said zone, introducing a portion of said withdrawn overhead product stream into an upper portion of said zone as reflux, withdrawing a kettle product stream comprising said second component from a lower portion of said zone, withdrawing an intermediate product stream comprising said third component from an intermediate portion of said zone, adding heat to the lower portion of said zone, analyzing the overhead product stream to determine the concentration of said third component therein, adjusting said reflux responsive to said third component concentration in said overhead stream, analyzing the kettle product stream to determine the concentration of said third component therein, adjusting the flow of kettle product through a heating zone responsive to said third component concentration in said kettle product stream, analyzing said intermediate product to determine the concentration of said first and second components in said intermediate product, and adjusting the temperature of said feed mixture responsive to the analysis of said intermediate fraction so as to tend to maintain the analyzed concentration of said first and second components therein at a minimum value.
